SHEET METAL RECEPTACLE

Jacques Stanitz and George D. Boyer, Warren,
Ohio, assignors to The Youngstown Pressed
Steel Company, Warren, Ohio, a corporation of
Ohio

Application July 24, 1933, Serial No. 681,832

10 Claims. (Cl. 220—72)

The invention relates to sheet metal receptacles; and more particularly the invention relates to a sheet metal receptacle having integral bottom and side walls all formed or drawn from a single piece or blank of sheet or plate metal, and having a series of grooves, channels, furrows, flutes, and the like, forming ribs, corrugations and the like, extending upwards in the side walls of the receptacle from an intermediate portion of a curved corner wall provided between the integral bottom and side walls; and this application is a continuation in part of the common subject matter contained in our copending application entitled Tub for washing machine, filed 15 December 7, 1932, Serial No. 646,208.

Such receptacles may be used for many purposes, but the same are especially adapted for use as tubs for power-driven, rotary-oscillating-agitator equipped washing machines. It is desirable that such tubs be covered with a vitreous enamel coating, and although enamel coated tubs with corrugated side walls have been made, difficulties have been encountered in connection with prior types of such tubs. 25

Tubs for washing machines have been proposed in which the side walls are corrugated and in which the tubs are made with integral bottom and side walls. However, the corrugations in such tubs do not extend entirely to and merge 30 into the corner wall between the side walls and bottom wall; but the lower ends of the corrugations stop short of the corner wall, leaving an annular recess thereunder.

When such tubs are used in washing machines 35 having power-driven, rotary-oscillating-agitators the annular recess at the bottom of the tub forms an obstruction or resistance to the water forced outwards along the bottom wall and prevents a maximum amount of the same from rising vertically upwards along the side walls, thus reducing the efficiency of the washing machine.

It is therefore an object of the present invention to provide a sheet metal receptacle adapted for use as a tub for a washing machine, which has 45 a series of grooves, channels, furrows, flutes, and the like, forming ribs, corrugations, and the like, in the side walls of the receptacle, and in which no annular recess is present in the tube below the ends of the ribs or corrugations, as by extending the ribs or corrugations to and merging the same into a curved corner wall provided 50 between the tub bottom and side walls.

Tubs for washing machines have also been proposed in which the side walls are corrugated, to 55 which side walls a bottom wall is seamed or other-

wise secured. However, the formation of a seam between the side walls and bottom wall of such a tub, or the securing of the tub side and bottom walls together by any other means, prevents a satisfactory, uniform, attractive and efficient vitreous enamel coating from being applied to the tub, particularly at the place where the side and bottom walls are secured together.

It is therefore a further object of the present invention to provide a sheet metal receptacle having integral bottom and side walls all formed from a single piece or blank of sheet or plate metal, which has a series of grooves, and the like, forming ribs, corrugations, and the like, in the side walls thereof extending upwards in the side 15 walls from an intermediate portion of a curved corner wall provided between the integral bottom and side walls.

It is a further object of the present invention to provide a sheet metal receptacle having integral bottom and side walls, the side walls having grooves therein extending upwards from an intermediate portion of a curved corner wall provided between the integral bottom and side walls, the grooves having a uniform contour throughout their length, the low point of the grooves having a uniform depth throughout the extent of the grooves, the grooves having either an equal or a varying length, and any element of the grooves lying in a vertical plane or in a vertical 20 cylindrical surface.

And finally, it is an object of the present invention to provide sheet metal receptacles having corrugated side walls, which have pleasing, attractive and distinctive appearances, which 35 may be formed and corrugated by simple drawing operations in an inexpensive manner, and which may thereafter be provided with a uniform vitreous enamel coating.

These and other objects may be obtained by 40 the sheet metal receptacles, constructions, arrangements and elements hereinafter described in detail and claimed, preferred embodiments of which are shown in the accompanying drawings, which may be stated in general terms as including in a sheet metal receptacle, integral bottom and side walls with a curved corner wall therebetween formed from a single piece or blank of sheet or plate metal, there being a series of preferably uniformly spaced continuous grooves, 45 channels, furrows, flutes, and the like in said side walls forming continuous ribs, corrugations, and the like, preferably protruding inwardly into the receptacle, said grooves having uniform contour 50 throughout their length and extending upwards 55

in said side walls from an intermediate portion of said curved corner wall.

In the drawings,

Figure 1 is a top plan view, with parts broken away and in section, of one embodiment of improved sheet metal receptacle, utilized as a tub for a washing machine, a usual type of washing machine agitator being shown therein;

Fig. 2 is a side elevation of the improved sheet metal receptacle shown in Fig. 1, part of the same being broken away and in section as on the line 2—2, Fig. 1;

Fig. 3 is an enlarged fragmentary sectional view of the lower corner of the receptacle shown in Fig. 1, illustrating the manner in which the side wall corrugations merge into an intermediate portion of the curved corner wall, taken on the line 3—3, Fig. 1;

Fig. 4 is a side elevation of an improved receptacle embodying a modified form of side wall corrugations;

Fig. 5 is an enlarged fragmentary sectional view of the corrugated side wall of the receptacle shown in Fig. 4, taken on the line 5—5, Fig. 4;

Fig. 6 is an enlarged fragmentary sectional view of the curved corner wall of the receptacle shown in Fig. 4, taken on the line 6—6, Fig. 4;

Fig. 7 is a side elevation of an improved receptacle embodying side wall corrugations of varying length;

Fig. 8 is an enlarged fragmentary sectional view of the corrugated side wall of the receptacle shown in Fig. 7, taken on the line 8—8, Fig. 7;

Fig. 9 is an enlarged fragmentary sectional view of the curved corner wall of the receptacle shown in Fig. 7, taken on the line 9—9, Fig. 7;

Fig. 10 is a side elevation of an improved receptacle embodying helical side wall corrugations;

Fig. 11 is an enlarged fragmentary sectional view of the corrugated side wall of the receptacle shown in Fig. 10, taken on the line 11—11, Fig. 10; and

Fig. 12 is an enlarged fragmentary sectional view of the curved corner wall of the receptacle shown in Fig. 10, taken on the line 12—12, Fig. 10.

Similar numerals refer to similar parts throughout the various figures of the drawings.

One embodiment of the improved sheet metal receptacle is indicated generally at 13 in Figs. 1 and 3 wherein the same is utilized as a tub for a power driven washing machine (not shown) having a usual rotary oscillating agitator 14.

The receptacle 13 includes a bottom wall 15, preferably cylindrical side walls 16, integral with the bottom wall, and there being a curved corner wall 17 extending from the place 18 where it merges with the bottom wall 15 to the place 19 where it merges with the side walls 16 (Fig. 2).

The bottom wall 15, when the receptacle is utilized as a washing machine tub, may be provided with any suitable drain opening 20; and a portion of the bottom wall 15 is preferably offset at 21 from the remainder thereof, adjacent to the agitator 14, the offset portion 21 preferably being provided with an opening 22 through which the driving means for the agitator 14 is connected with the agitator.

The upper extremities of the side walls 16 are preferably provided with an annular groove 23 and preferably terminate in an outwardly downturned bead 24 when the receptacle is used as a tub for a washing machine.

A series of preferably uniformly spaced continuous grooves, channels, furrows, flutes and the

like, indicated at 25, are provided in the side walls of the receptacle extending upwards in the side walls from a portion 26 of the curved corner wall intermediate the extremities 18 and 19 of the curved corner wall (Fig. 3) to points spaced below the top of the side walls 16 and the groove 25 therein. The said grooves 25 thus form continuous ribs 27 in the side walls 16 protruding inwardly into the receptacle 13, as best shown in Figs. 1 and 2; and as indicated, the grooves 25 have a uniform depth, width and contour in cross section throughout their extent.

Likewise, any element of any of the grooves 25 (Fig. 2) lies in a vertical cylindrical surface, from the intermediate portion 26 of the curved corner wall where the grooves begin, to but not including the upper ends 28 of the grooves 25 which are rounded outwardly as shown to merge into the side walls 16.

By this peculiar arrangement, which constitutes an important feature of the present invention, in which the bottom ends of the grooves 25 extend from an intermediate portion of the curved corner wall 17, the formation of an annular recess within the container lying beneath the ends of the corrugations is avoided, such a recess, however, being present above the upper ends 28 of the grooves 25, as indicated at 29 in the drawings.

When the improved receptacle is used as a washing machine tub, the elimination of a recess below the ends of the corrugations, and the merging of the lower ends of the corrugations into the curved corner wall enables a maximum amount of the water thrown outwards along the bottom wall by the agitator to round the curved corner wall and to flow upward along the tub side walls, thus producing maximum washing efficiency.

In Figs. 4, 5 and 6, another embodiment of improved sheet metal receptacle 113 is shown, which is identical in all respects with the construction shown in Figs. 1, 2 and 3, excepting that the spaced parallel vertical grooves 125, which extend upwards in the side walls 116 from an intermediate portion 126 of the curved corner wall 117 to points spaced below the top of the side walls 116, are compound grooves and comprise preferably substantially flattened portions 125a and a curved portion 125b.

Another modified form of improved receptacle 213 is shown in Figs. 7, 8 and 9, which is identical in all respects with that shown in the preceding figures of the drawings, excepting only that the spaced grooves 225, which extend upwards in the side walls 216 from an intermediate portion 226 of the curved corner wall 217 thereof to points spaced below the top of the side walls 216, have a varying length as best shown in Fig. 7.

Still another modified form of improved receptacle is shown at 313 in Figs. 10, 11 and 12, and the same is similar in all respects with the forms of the invention shown in the preceding figures of the drawings, excepting only that the grooves 325 which extend upwards in the side walls 316 of the receptacle from an intermediate portion 326 of the curved corner wall 317 to points spaced below the top of the side walls 316, are parallel helical grooves, as best shown in Fig. 10.

The improved sheet metal receptacles may preferably be made in apparatus such as is disclosed in our copending application, Serial No. 606,971, filed April 22, 1932, entitled Corrugating apparatus, matured in Patent No. 1,919,869, dated July 75

- 25, 1933, according to the method set forth in our copending application filed July 24, 1933, Serial No. 681,833, entitled Method of corrugating sheet metal receptacles, maturing in Patent No. 5 2,003,981, dated June 4, 1935, as by drawing a suitable receptacle with cylindrical side walls, an integral bottom wall and a curved corner wall therebetween in suitable dies from a single blank of metal, and then forming spaced grooves in 10 the side walls extending upwards from an intermediate portion of the corner wall to points spaced below the top of the side walls, by telescoping the receptacle blank upon a groove male die having outer bounding surfaces conforming to 15 the inner surfaces of the receptacle blank and by then relatively telescoping said male die with the receptacle blank thereon in a female die having rolling die means corresponding to said male die grooves, for forcing the receptacle blank 20 into the female die to form the grooves in the blank side walls progressively upwards from the curved corner wall thereof.

Accordingly, the present invention provides improved sheet metal receptacles having integral bottom and vertical side walls formed from a single piece of sheet metal having a series of grooves forming ribs extending upwards in the side walls of the receptacles from an intermediate portion of a curved corner wall provided between the bottom and side walls, without there being any annular recess present in the receptacles below the lower ends of the ribs or corrugations, which receptacles may be readily coated with a uniform and efficient vitreous enamel coating, and which receptacles have a pleasing, attractive and distinctive appearance and may be made in an inexpensive manner.

The term "sheet metal" used herein and in the appended claims is intended to refer to sheet or plate metal according to the side wall thickness which it may be desired to provide. Likewise, it is not intended to limit the scope of the present invention to receptacles made of sheet steel and provided with a vitreous enamel coating, because it is clear that the improved receptacles may be made from copper, stainless steel, or other desired metals.

The term "grooves" utilized broadly herein and in the appended claims, is intended to include channels, furrows, flutes, and the like of the desired cross sectional shape; it being clear that for particular purposes the contour of the grooves in cross section may have any desired shape so as to produce a serrated, ribbed or corrugated inner side wall surface for the receptacle.

While we have shown and described certain embodiments of our invention, it is to be understood that the invention is capable of many modifications so long as the side wall grooves or ribs are continuous and extend upwards in the side walls from an intermediate portion of the curved corner wall between the integral bottom and side walls of the receptacle. Changes, therefore, in the construction and arrangement may be made without departing from the spirit and scope of the invention, as disclosed in the appended claims.

We claim:—

1. In a sheet metal receptacle having integral bottom and side walls with a curved corner wall therebetween, a series of spaced continuous grooves in said side walls forming continuous ribs therein, said grooves beginning at and extending upwards in said side walls from an intermediate portion of said curved corner wall, and the upper ends of said grooves merging into said side walls at points spaced below the top of said side walls.
2. In a sheet metal receptacle having integral bottom and side walls with a curved corner wall therebetween, a series of spaced continuous grooves in said side walls forming continuous ribs therein, said grooves beginning at and extending upwards in said side walls from an intermediate portion of said curved corner wall, and having a uniform contour in cross section throughout their extent, and the upper ends of said grooves merging into said side walls at points spaced below the top of said side walls. 5
3. In a sheet metal receptacle having integral bottom and side walls with a curved corner wall therebetween, a series of uniformly spaced continuous grooves in said side walls forming continuous ribs therein protruding inwardly into the receptacle, said grooves beginning at and extending upwards in said side walls from an intermediate portion of said curved corner wall, and the upper ends of said grooves merging into said side walls at points spaced below the top of said side walls. 10
4. In a sheet metal receptacle having integral bottom and side walls with a curved corner wall therebetween, a series of spaced grooves in said side walls forming ribs therein, said grooves beginning at and extending upwards in said side walls from an intermediate portion of said curved corner wall and having a uniform depth and contour throughout their extent. 15
5. In a sheet metal receptacle having integral bottom and side walls with a curved corner wall therebetween, a series of spaced grooves in said side walls forming ribs therein protruding inwardly into the receptacle, said grooves beginning at and extending upwards in said side walls from an intermediate portion of said curved corner wall, and having uniform depth and width throughout their extent. 20
6. A sheet metal receptacle having integral bottom and side walls with a curved corner wall therebetween, a series of spaced continuous grooves in said side walls forming continuous ribs therein, said grooves beginning at and extending upwards in said side walls from an intermediate portion of said curved corner wall, the upper ends of said grooves merging into said side walls at points spaced below the top of said side walls, and a portion of said bottom wall being offset from 25 the remainder thereof. 30
7. In a sheet metal receptacle having integral bottom and cylindrical side walls with a curved corner wall therebetween, a series of spaced grooves in said side walls forming ribs therein, said grooves beginning at and extending upwards in said side walls from an intermediate portion of said curved corner wall and having a uniform contour in cross section throughout their extent, and any element of any of the grooves lying in 35 a vertical cylindrical surface. 40
8. In a sheet metal receptacle having integral bottom and cylindrical side walls with a curved corner wall therebetween, a series of spaced parallel vertical grooves in said side walls forming ribs therein, said vertical grooves beginning at and extending upwards in said side walls from an intermediate portion of said curved corner wall and having a uniform contour in cross section throughout their extent. 45
9. In a sheet metal receptacle having integral bottom and cylindrical side walls with a curved corner wall therebetween, a series of spaced grooves in said side walls forming ribs therein, said grooves beginning at and extending upwards in said side walls from 50 an intermediate portion of said curved corner wall and having a uniform contour in cross section throughout their extent. 55

in said side walls each from an intermediate portion of said curved corner wall and having a uniform contour in cross section throughout their extent, and the grooves being of varying length.

5 10. In a sheet metal receptacle having integral bottom and cylindrical side walls with a curved corner wall therebetween, a series of spaced parallel helical grooves in said side walls form-

ing ribs therein, said helical grooves beginning at and extending upwards in said side walls from an intermediate portion of said curved corner wall and having a uniform contour in cross section throughout their extent.
